CHEST PROTECTOR

Murray Morgan, Hoboken, N. J.

Application March 17, 1944, Serial No. 526,909

3 Claims. (Cl. 2-92)

This invention relates to new and useful improvements in a chest protector for men's and women's coats.

More particularly, the invention proposes a chest protector characterized by a triangularly shaped sheet-like member for extending across one's chest beneath a coat, and fasteners for releasably supporting said member to said coat.

More particularly, the invention proposes to characterize said sheet-like member by the fact that it is formed from paper, flexible board or similar materials.

The invention also proposes providing the top edge of said sheet-like member with a rolled edge so that it does not hurt one's neck or chest.

A still further object of the invention resides in a novel arrangement by which the triangularly shaped sheet-like member may be extended or contracted to fit chests of different widths.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an illustration of a person wearing a coat provided with a chest protector constructed in accordance with this invention.

Fig. 2 is a perspective view of the chest protector, per se.

Fig. 3 is a perspective view of a chest protector constructed in accordance with another form of this invention.

Fig. 4 is an elevational view of a chest protector embodying still another form of this invention.

Fig. 5 is a fragmentary enlarged sectional view taken on the line 5—5 of Fig. 4.

The chest protector for men's and women's coats, according to this invention, comprises a triangularly shaped sheet-like member 10 for extending across the chest beneath one's coat. Said member 10 is provided with fasteners 11 by which it may be releasably supported on the coat. The chest protector is used in conjunction with a coat 12 provided with complementary fastening elements 11' for coaction with the fastening elements 11. The top edge of the member 10 is cut curved, indicated by reference numeral 14 so as to comfortably fit across one's chest beneath the neck.

The chest protector is worn by slipping it beneath one's coat and engaging the fasteners 11

15 with the complementary fastener's 11' secured to the coat for this purpose.

In Fig. 3 a modified form of the invention is disclosed which is similar to the first form distinguishing merely in the fact that the top edge of the sheet-like member 10 is provided with a rolled edge 15. In other respects this form of the invention is similar to that previously shown and like reference numerals identify like parts in each of the several views. This rolled edge prevents the top edge of the member 10 from cutting or injuring a wearer.

In Figs. 4 and 5 still another modified form of the invention is shown in which the chest protector includes a triangularly shaped sheet-like member 16 for extending across one's chest beneath a coat. This member 16 is preferably formed from paper, heavy paper or other flexible and creasable sheet material. It is provided with a vertical pleat 17 having a back layer 17^a continuing into a central layer 17^b which continues into a front layer 17^c. The pleat 17 extends the entire height of the sheet-like member 16.

Several fasteners 18 are mounted through the pleat 17 at one side of the pleat for releasably holding the pleat closed. The front layer 17^c is formed with transverse slots 19 in which the fastener 18 may slide. Each fastener 18 includes a screw 20 having a turnable and threaded nut 21 at one end and a head at the other end beneath which there is a gripping or friction washer 22.

A spring-like frame 23 is mounted within the pleat 17 for holding it in formation. This spring frame 23 is formed of spring wire and has end portions 24 looped about the screws 20. It has a central portion engaging in between the layers of the pleat 17 for holding the pleat stretched. The spring-like frame 23 has several convolutions 25 which permits it to expand and contract.

The member 16 is also provided with fastener elements 11 by which it may be mounted within a coat. The width of the member 16 may be varied by loosening the nuts 21 and then pulling the back layer 17^a in one direction and the front layer 17^c in the other direction so as to reduce the width of the pleat 17. The spring-like frame 23 is merely compressed during this operation. The nuts 21 are then turned tight.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A chest protector for men's and women's coats comprising a triangularly shaped sheet-like member for extending across one's chest beneath one's coat and fasteners for releasably supporting said member to said coat, said sheet-like member having a vertical pleat consisting of a back layer continuing into a central layer, continuing into an outer layer, and studs passing through aligned openings in two of the layers and an elongated slot in the other of said layers for holding these layers in relative positions to control the width of said protector.

2. A chest protector for men's and women's coats comprising a triangularly shaped sheet-like member for extending across one's chest beneath one's coat and fasteners for releasably supporting said member to said coat, said sheet-like member having a vertical pleat consisting of a back layer continuing into a central layer, continuing into an outer layer, and studs for holding

these layers in relative positions and a frame-like spring mounted within the pleat and mounted against said studs for holding the pleat in formation.

3. A chest protector for men's and women's coats, comprising a triangularly shaped sheet-like member for extending across one's chest beneath one's coat and fasteners for releasably supporting said member to said coat, said sheet-like member having a vertical pleat consisting of a back layer continuing into a central layer, continuing into an outer layer, and studs for holding these layers in relative positions and a frame-like spring mounted within the pleat and mounted against said studs for holding the pleat in formation, said frame-like spring having its ends engaging said studs and an intermediate area bearing against said pleat, and expandable convolutions formed in said frame-like spring between its ends and said intermediate area permitting said spring to extend itself in all adjusted positions of said pleat to maintain said pleat formed.

MURRAY MORGAN.
